Primary Examiner — Mary Ann Calabrese

Assistant Examiner — Catherine Ho

(57) CLAIM

The ornamental design for a card holder, as shown and described.

DESCRIPTION

FIG. 1 is a front view of a card holder showing my new design;

FIG. 2 is a rear view of the card holder;

FIG. 3 is a right side view of the card holder;

FIG. 4 is a left side view of the card holder;

FIG. 5 is a top view of the card holder;

FIG. 6 is a bottom view of the card holder; and,

FIG. 7 is a top front side perspective view of the card holder in use.

The broken lines in FIG. 7 are illustrative of environmental structure and form no part of the claimed design.

1 Claim, 5 Drawing Sheets(56)
